Filed Sept. 28, 1959, Ser. No. 57,710

Term of patent 14 years

(Cl. D13—1)

FIG. 1
FIG. 2

FIGURE 1 is a front elevational view of a mobile service station showing our new design; and

FIGURE 2 is an end elevational view thereof.

The lining on the drawing represents color contrast. The rear, the end and the top of the building, which are not shown, are substantially plain.

We claim:

The ornamental design for a mobile service station, as shown and described.
